UNITED STATES PATENT OFFICE.

BENJAMIN A. DALAND, OF PHILADELPHIA, PENNSYLVANIA.

DESIGN FOR A SOAP-CAKE.

SPECIFICATION forming part of Design No. 14,240, dated August 28, 1883.

Application filed December 20, 1882. Term of patent 7 years.

To all whom it may concern:

Be it known that I, BENJAMIN A. DALAND, of the city of Philadelphia, county of Philadelphia, and State of Pennsylvania, have invented an Improved Design for Soap-Cakes, of which the following is a specification.

My invention has reference to designs for soap-cakes; and it consists in a soap-cake shaped into the form of a trunk or trunk-vase, in which there are panels adapted to receive the name of the soap or manufacturer, or both, on one or more of its sides, and in details, as set forth in the following specification, and shown in the accompanying drawings, which form part thereof, and referred to in the claim.

Heretofore soap has been formed into cubical blocks or bars, or into the forms of animals or children.

The object of my invention is to form the soap, especially fine toilet-soaps, into blocks shaped like a trunk, whereby the same shall have great attractive qualities, and yet is just as well adapted for use as the cubical or plain cakes.

In the drawings, Figure 1 is a perspective view of a cake of soap formed after my improved design. Fig. 2 is an elevation of same, looking from the rear.

A represents the body of the trunk; B, the

lid; C C, the ribs or protector-bars; D, the lock; E, the lifting-straps on the ends. F represents the top ribs, the same being curved to the curve of the lid B. G are panels on the front of the trunk, and are adapted to receive 35 the name or suitable words, or both.

The back of the trunk may also be provided with a panel, H, and the ends of the cake are plain, with the exception of the handles E, and, if desired, the bars C.

The top, front, and back of the cake are otherwise ornamented like a trunk, and may contain configurations representing all of the details of construction of any ordinary trunk.

That part representing the leather may be 45 more or less roughened in its surface.

Having now described my invention, what I claim as new, and desire to secure by Letters Patent, is—

A cake of soap formed with the external 50 representation of a trunk, having one or more of its sides provided with panels adapted to receive names or suitable words, substantially as shown.

In testimony of which invention I hereunto 55 set my hand.

BENJAMIN A. DALAND.
